US0D1045822S

(12) **United States Design Patent** (10) Patent No.: **US D1,045,822 S**
(45) Date of Patent: ** *Oct. 8, 2024

(54) **HEADPHONE**

(71) Applicant: **Shenzhen Boman Acoustics Co., Ltd.**,
Shenzhen (CN)

(72) Inventor: **Dongmei Liu**, Shenzhen (CN)

(*) Notice: This patent is subject to a terminal disclaimer.

(**) Term: **15 Years**

(21) Appl. No.: **29/925,170**

(22) Filed: **Jan. 23, 2024**

(51) LOC (14) Cl. **14-01**

(52) U.S. Cl.

USPC **D14/205**

(58) **Field of Classification Search**

(57) **CLAIM**

The ornamental design for a headphone, as shown and described.

DESCRIPTION

FIG. 1 is a perspective view of a headphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
